[57] CLAIM

The ornamental design for a simplified easy to read caliper, as shown and described.

DESCRIPTION

FIG. 1 is a perspective view of the simplified easy to read caliper of the present invention;

FIG. 2 is a top plan view of the simplified easy to read caliper shown in FIG. 1;

FIG. 3 is a bottom view of the simplified easy to read caliper of FIGS. 1 and 2;

FIG. 4 is a left end view of the simplified easy to read caliper of FIGS. 1-3;

FIG. 5 is a rear view of the simplified easy to read caliper of FIGS. 1-4;

FIG. 6 is a right end view of the simplified easy to read caliper of FIGS. 1-5; and,

FIG. 7 is a top view of the simplified easy to read caliper of FIGS. 1-6.
